(57) **CLAIM**

The ornamental design for a toe cap for footwear, as shown and described.

DESCRIPTION

FIG. 1 is a perspective view of my toe cap for footwear; FIG. 2 is a back view thereof; FIG. 3 is a front view thereof; FIG. 4 is a left view thereof; FIG. 5 is a right view thereof; FIG. 6 is a top view thereof; and, FIG. 7 is a bottom view thereof.

The broken lines shown in the drawings represent portions of the toe cap for footwear that form no part of the claimed design. The dot-dashed lines in the figures represent boundary lines defining a boundary of certain aspects of the claimed design. It is to be understood that the claimed design extends to but does not include the defined boundary. For instance, dot-dashed lines are used to, *inter alia*, define a boundary of or within the toe cap, it being understood that the claimed design extends to but does not include the boundary.
